CLAIM

The ornamental design for an ear protector, as shown and described.

DESCRIPTION

FIG. 1 is a front, bottom perspective view of an ear protector, showing our new design;

FIG. 2 is a right side view thereof;

FIG. 3 is a front view thereof;

FIG. 4 is a left side view thereof;

FIG. 5 is rear view thereof;

FIG. 6 is a top view thereof;

FIG. 7 is a bottom view thereof; and,

FIG. 8 is a front perspective view thereof, shown in a used condition with a head set shown in broken lines.

The broken lines in the drawings depict structure that forms no part of the claimed design.

1 Claim, 7 Drawing Sheets
